Short needles.—Quantity on main stalks and

on laterals—none.

I claim:

A new and distinct variety of rose plant of

the polyantha class, characterized as to novelty

by its mound-like, vigorous and free-growing

habits of growth, by its profusion of long-lasting

blooms of Shrimp Pink color, lightly overcast

with La France Pink, and by its freedom of winter

forcing when used as a pot rose, substantially

as shown and described.

EUGENE S. BOERNER.
